[57] CLAIM

The ornamental design for a paint tip holder, as shown and described.

DESCRIPTION

FIG. 1 is a perspective view of a paint tip holder showing my new design, with the retaining strap of the holder shown in an unlatched condition and the box-like container on the left side of the holder is shown in a closed condition;

FIG. 2 is a top plan view of the paint tip holder shown in FIG. 1;

FIG. 3 is a bottom plan view of the paint tip holder shown in FIG. 1;

FIG. 4 is a front elevational view of the paint tip holder of FIG. 1;

FIG. 5 is a rear elevational view of the paint tip holder of FIG. 1;

FIG. 6 is a right side elevational view of the paint tip holder of FIG. 1;

FIG. 7 is a left side elevational view of the paint tip holder of FIG. 1;

FIG. 8 is a perspective view of the paint tip holder of FIG. 1 wherein the retaining strap is shown in an unlatched condition and the box-like container on the left side of the holder is shown in an open condition; and,
